UNITED STATES PATENT OFFICE.

JOHN T. QUIGLEY, OF BOSTON, MASSACHUSETTS, ASSIGNOR TO COSTMETER COMPANY, OF BOSTON, MASSACHUSETTS, A CORPORATION OF MASSACHUSETTS.

FILING AND INDEXING EQUIPMENT.

Application filed November 2, 1918. Serial No. 260,845.

To all whom it may concern:

Be it known that I, JOHN T. QUIGLEY, a citizen of the United States, and a resident of Boston, in the county of Suffolk and State 5 of Massachusetts, have invented an Improvement in Filing and Indexing Equipment, of which the following description, in connection with the accompanying drawings, is a specification, like characters on the drawings representing like parts.

This invention relates to filing and indexing equipments of the class in which the sheets are arranged with their identification-bearing margins in overlapping relation- 15 ship, and is more especially concerned with novel sheets and sheet-holders having provision on the one hand to permit the sheets to be detached from their respective sheet-holders, and reattached thereto or inter- 20 changed at will, and on the other hand to permit the sheets and sheet-holders to be detached from the frame or mounting and reattached thereto or interchanged at will.

My invention will be best understood by 25 reference to the following description, when taken in connection with the accompanying drawings of one specific embodiment there- 30 of, while its scope will be more particularly pointed out in the appended claims.

In the drawings:

Fig. 1 is a front elevation of a filing and indexing equipment embodying my invention;

Fig. 2 is an elevation of a pair of sheet- 35 holders and a sheet, the latter being unfolded;

Fig. 3 is a sectional view on line 3—3 of Fig. 1, illustrating a sheet flexed preparatory to moving the same from the mounting 40 or frame;

Fig. 4 is a longitudinal sectional view of one of the sheet-holders on an enlarged scale; and

Fig. 5 is an end elevation of the sheet- 45 holder viewed from the right-hand side of Fig. 4.

Referring to the drawings, and to the embodiment of my invention which is illustrated therein, I have shown for purposes 50 of exemplification a filing and indexing equipment comprising a plurality of sheets 10, which may be and are herein folded along a line 11. The sheet is held by means herein comprising two individually distinct members having readily attachable and de-

tachable independent connection with the sheet. These members may take various forms, and may be otherwise suitably secured to the sheet, but in the present example, the latter is provided with two sets of 60 perforations 12, herein arranged in pairs, to receive members 13, each extending along one face of the sheet, through a perforation of one set, then along the other face of the sheet through another perforation of such 65 set, and finally along the first face of said sheet, as clearly shown in Fig. 2. The sheet is not necessarily folded, but where, as in the present case, a folded sheet is used, the perforations are adjacent the line of the fold 70 and preferably at one side of the latter, as shown in Fig. 2. In such case, also, the sheet is folded so that the inner ends of the sheet-holders are received within the fold of 75 the sheet, and thus bear on the inner face of 75 the sheet-holder when the latter is unfolded, as shown in Fig. 2.

Where the sheet-holder is threaded in and out through the perforations, as herein shown, the deformation of the sheet resulting therefrom tends to produce a frictional resistance to the sliding movement of the sheet-holder, and this is desirable because it tends to prevent accidental withdrawal of the sheet-holder. If desired, however, this 80 frictional resistance may be increased by providing a sheet-holder having provision for yieldingly engaging opposite edges of the perforations. To this end, I have herein provided sheet-holders, each of which comprises two generally parallel portions having a tendency to spring apart, and thereby to engage the edges of the perforations with spring pressure. One convenient way of 85 accomplishing this is to provide a sheet-holder 90 made of a piece of wire bent to form a loop, as best shown in Fig. 4, the terminal portions of said wire being suitably secured together. This may be done in various ways, as by providing a sleeve 14 encircling the 95 terminal portions of the wire, and appropriately secured thereon as by providing a wedge-block 15 forced into the space between the terminal portions of the wire, and clamping the latter firmly within the sleeve, as clearly shown in Figs. 4 and 5.

Preferably, the sleeves 14 are cylindrical in form, and constitute trunnions about whose axes the sheet and sheet-holders may be swung, the latter to this end being mount-

ed in appropriate bearings. In the present embodiment, these bearings are formed by a frame or mounting 16 having inwardly facing flanges 17 forming channels 18, in which 5 the trunnions are received. The trunnions contact with one another, and maintain the identification-bearing margins of the sheets in appropriately spaced relationship, as shown in Fig. 1, while still permitting the 10 sheets to be turned to and fro to expose either face to view. The sheet-holders are maintained in their proper places in the channels by the provision of suitable upper and lower stops 19 and 20, shown in Fig. 1. 15 It should now be apparent that the sheet-holders may be removed from and replaced in their respective sheets, and the latter may be interchanged or renewed from time to time, as circumstances may require. This is 20 of special advantage in case it is desired to make records on the sheets by the use of a typewriter, as under these circumstances, the sheet-holders may be removed preparatory to making the record, and reattached when 25 the record is completed and the sheet is to be reattached to the mounting. The latter operation is well illustrated in Fig. 3, in which the sheet is shown fixed or bowed to permit the trunnions to be withdrawn from, 30 or replaced in, the channels. It is obvious that by providing a sheet of sufficient stability, the latter will lie perfectly flat, and cannot be removed from the mounting, except by purposely flexing the same to withdraw 35 its trunnions from the channels.

Having thus described one specific embodiment of my invention, what I claim and desire by Letters Patent to secure is:

1. In an equipment of the class described, 40 the combination of a perforated sheet, sheet-holding means comprising two individually distinct members received in the perforations and having readily attachable and detachable independent connection with said 45 sheet, said members presenting trunnions, and means providing bearings in which said trunnions are received.

2. In an equipment of the class described, 50 the combination of a sheet provided with perforations, sheet-holding means comprising two individually distinct members mounted to slide into and out of said perforations, and means providing supports for said members.

55 3. In an equipment of the class described, the combination of a folded sheet provided with perforations adjacent the fold, sheet-holding means comprising two individually distinct members received in said fold and 60 said perforations and mounted to slide independently into and out of said perforations, and means providing supports for said members.

65 4. In an equipment of the class described, the combination of a sheet provided with

two sets of perforations, sheet-holding means comprising two individually distinct members, each extending along one face of said sheet, through a perforation of one set, then along the other face of said sheet, 70 then through another perforation of such set, and finally along the first face of said sheet, and means providing supports for said members.

5. In an equipment of the class described, 75 the combination of a folded sheet provided with two sets of perforations at one side of the line of the fold, sheet-holding means comprising two individually distinct members extending along within said fold, 80 through a perforation of one set, then along without said fold, then through another perforation of such set, and finally along within said fold, and means providing supports for the outer ends of said members. 85

6. In an equipment of the class described, 90 the combination of a sheet provided with two sets of perforations, sheet-holding means comprising two individually distinct members, each received in the perforations 95 of one of said sets and having provision yieldingly to engage opposite sides of said perforations.

7. In an equipment of the class described, 100 the combination of a sheet provided with two sets of perforations, sheet-holding means comprising two individually distinct members, each received in the perforations of one of said sets and having provision to engage said sheet with spring pressure. 105

8. In an equipment of the class described, 110 the combination of a sheet provided with two sets of perforations, sheet-holding means comprising two individually distinct members, each received in the perforations of one of said sets and each comprising two generally parallel portions frictionally engaging opposite edges of the perforations in which they are received.

9. In an equipment of the class described, 115 the combination of a sheet provided with two sets of perforations, sheet-holding means comprising two individually distinct members, each received in the perforations of one of said sets and each comprising a piece of wire bent to form two generally parallel portions frictionally engaging opposite edges of the perforations in which they are received.

10. In an equipment of the class described, 120 the combination of a sheet provided with two sets of perforations, sheet-holding means comprising two individually distinct members, each received in the perforations of one of said sets and each comprising a piece 125 of wire bent to form a loop.

11. In an equipment of the class described, 130 the combination of a sheet provided with two sets of perforations, sheet-holding means comprising two individually distinct mem-

bers, each received in the perforations of one of said sets and each comprising a piece of wire bent to form a loop, the terminal portions of said wire being secured together.

12. In an equipment of the class described, the combination of a sheet provided with two sets of perforations, sheet-holding means comprising two individually distinct members, each received in the perforations of one of said sets and each comprising a piece of wire bent to form a loop, and a sleeve enclosing the terminal portions of each wire.

13. In an equipment of the class described, the combination of a sheet provided with two sets of perforations, sheet-holding means comprising two individually distinct members, each received in the perforations of one of said sets and each comprising a

piece of wire bent to form a loop and a cylindrical trunnion to which the terminal portions of each wire are secured.

14. In a file, the combination of a series of perforated sheets having overlapping margins, and a series of sheet-holding means, 25 the sheet-holding means of each sheet having a part received in a perforation of such sheet and preventing separation in a direction transverse to said margins, said part being normally retained in said perforation 30 by resilient action and being withdrawable from said perforation by relative movement of said sheet and sheet-holding means in a direction parallel with said margins.

In testimony whereof, I have signed my 35 name to this specification.

JOHN T. QUIGLEY.
